UNITED STATES PATENT OFFICE.

ALFRED J. CHAMBERLAIN, OF WAUWATOSA, WISCONSIN.

CONTAINER.

Application filed August 27, 1927. Serial No. 215,799.

This invention relates in general to containers and more particularly to a pail especially designed for use with lacquers, although possessing wide adaptability and capacity for advantageous use.

Pails or containers for lacquer are required to have closures for their discharge openings, which have liquid-tight seals with the parts of the pail with which they co-act, and the pail and closure structure, as well as the seal, must be appropriately rugged and strong to withstand severe usage and handling to which they are subjected. Such containers will not be accepted for shipment unless they can withstand the so-called "drop test". Moreover, lacquer is used in a great many instances in air guns of the type in which the lacquer is poured into a small cup attached to the gun, and filling these air guns from a pail of conventional size requires provision of suitable pouring means. The problem is further complicated by the fact that lacquer must be stirred thoroughly before being used. In order to facilitate pouring, it has been the custom to use cans having restricted discharge necks, which are comparatively easy to seal and which facilitate pouring to some extent, but which make thorough stirring of the lacquer very difficult. Moreover, these cans must be boxed or crated for shipment as they are not adapted to withstand the rough usage. Heretofore a practical pail construction adapted to meet the various requirements of a container for lacquer or the like has not been available.

One of the principal objects of the invention is to provide a pail construction designed and adapted for use in shipping and dispensing lacquer.

Another object is to provide a pail construction of this character which is of simple yet strong and rugged construction, so as to be well adapted to withstand rough usage of actual conditions, as well as the so-called "drop test" and which, while providing a strong and liquid-tight seal for its closure, nevertheless facilitates the thorough stirring of the lacquer and further provides for easy and controlled pouring of the lacquer into the air guns or other similar receptacle without spilling or splashing of the lacquer.

A further object is to provide pail construction having these advantages and capacities and which embodies a suitable,

coated steel construction, so as to combine strength with a capacity to resist the attack of the solvents of the lacquer, thereby maintaining the structural integrity of the pail and avoiding impairment of the color or properties of the lacquer.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in diametrical vertical section showing the pail embodying the present invention;

Figure 2 is a plan view of such a pail with the cover or closure removed; and

Figure 3 is a fragmentary sectional view, similar to Figure 1, but showing a slightly modified construction.

Referring to the drawing, numeral 1 designates the body portion of the pail, which has a general form of a cylinder and is provided with a bottom 2. The upper end of the body of the pail is open and is provided with a rounded rim, or flange, 3, having a rolled and reinforced edge 3^a. A closure or cover 4 is provided for the upper open end of the container and this cover is held in position on the container by means of lugs 5, which are bent up under the rim 3, as illustrated by the dotted line in Figure 3. These lugs serve to clamp the flange 4^a of the cover forcibly against the gasket 6 interposed between the flange 4^a and a seat provided for the gasket on the rim 3, thereby affording very strong and rigid connection between the cover and the pail, as well as a liquid-tight joint. Hooks 5^a on the lugs 5 facilitate the withdrawal of the lugs and the removal of the cover 4. The construction as thus far described is more clearly and fully set out in my co-pending application, Serial No. 134198, filed September 13, 1926, for "container", and reference is made to such application for a detailed disclosure of these features. It is to be noted that the cover plate 4 has its body portion 4^b inset into the open top of the container slightly.

With the container structure so far described when the cover plate 4 is removed, the contents of the pail are readily accessible for stirring, but serious difficulty is encoun-

tered when it is necessary, as it often is, to pour the lacquer or other material in the pail into a small receptacle, such as an air gun cup and the like. The present invention provides for controlled and easy pouring without danger of spilling or splashing and does this without interfering with the free and thorough stirring of the contents of the pail. For this purpose a flat pouring breast 6 is provided and is positioned just below the body 4^b of the cover. Preferably this pouring breast consists of a flat metal plate of suitable form. In the embodiment shown the plate 6 is of segmental form and while this form has advantages, changes in the shape of plate 6 are contemplated. Around its curved edge plate 6 is provided with a depending flange 7 which engages the neck of the pail and is spot-welded or otherwise secured thereto. At a point contiguous with the neck of the pail, the pouring breast is provided with a discharge opening or port 8. The free edge of the pouring breast may be ribbed as at 9 to stiffen and strengthen it.

With this construction a large and unobstructed opening remains at the upper open end of the pail to provide for thorough and easy stirring and yet, when it is desirable to pour the contents of the pail into a small container this may readily be done, as the pouring breast restricts the discharge of the contents to a small and well defined stream which clears the rim of the pail and does not splash or scatter. In dispensing the contents of the pail, the pail is lifted by its bail handle and the flange of its bottom is grasped, to tilt the pail so as to lower the portion thereof adjacent to discharge outlet 8. The pouring breast prevents the contents of the pail from spilling and spreading over the rim and down the outside of the pail and constrains the discharging contents thereof to a controlled and well defined stream which issues from the outlet 8.

The form the invention shown in Figure 3 is identical with that just described, except as to the manner of mounting the pouring breast on the pail. In Figure 3 the pouring breast is designated at 15 and has a discharge outlet 16. The curved edge of the pouring breast is provided with an upwardly directed marginal flange 17 of substantially inverted U-shaped cross section. The flange 17 snugly embraces the rim 3 of the pail and has an extremity 18 bent around the rolled edge of the rim 3 to lock the pouring breast 15 in position. This arrangement does not interfere with the application and removal of the cover, and the application and removal of the cover does not disturb the mounting of the pouring breast. The shape, position, extent and general characteristics of the opening 8, especially as shown in Figures 1 and 2, promotes the for-

mation of a well defined and concentrated stream and tends to avoid spilling or scattering.

In order to give the pail the strength and durability required, the pail itself and its cover are constructed of sheet steel of suitable gauge. The desirability of utilizing sheet steel has long been recognized, but it has not been possible to use it heretofore for the reason that the steel is attacked by the solvents of the lacquer. This not only impairs the steel to some extent, but, what is more important, it discolors the lacquer and otherwise injuriously affects the properties of the lacquer. In applicant's construction this difficulty has been overcome by applying a thin and permanent coating on the steel which makes it effective to resist the action of the lacquer solvents or other lacquer ingredients. This coating consists of an alloy of lead and tin, there being about 93 parts of lead to 7 parts of tin. These two metals are mixed and heated to prepare a molten bath into which the pails and covers are dipped. The lead is comparatively inexpensive and is entirely resistant to the reaction of the solvents or other ingredients of the lacquer, but, of itself, it does not have the capacity to adhere as a continuous and uniform coating of the sheet steel. This deficiency in the adaptability of the lead is entirely remedied by an addition of a small amount of tin, which co-acts with the lead to provide a coating which easily adheres to the sheet steel and which penetrates and coats as well as seals all crevices or the like. The coating is indicated by a heavy line in drawing and is designated at C. It is to be understood that the proportions of lead and tin may be somewhat varied, but, in order to preserve the advantage of low cost, it is to utilize a relatively small amount of tin in a relatively large amount of lead.

Pails or containers embodying the present invention are usually constructed with a lengthwise seam, which must be welded to be liquid-tight. Drawing a single-piece pail is not a commercial possibility, due to the expense involved, but even were the pail drawn from a single piece, the drawing would have to be carried out in a succession of drawing operations, with annealing between each drawing operation. The welding in the one instance and the annealing in the other makes it necessary to first completely construct the pail liquid-tight and afterwards to coat it with the lacquer resisting material. Tin-plate or terneplate, that is, previously coated sheet steel, could not be used successfully because the welding or annealing would remove the coating.

The invention claimed is:

1. A container of the character described, comprising a pail body having an open upper end, a cover for said open upper end

and a pouring breast secured to the pail and located within the pail adjacent to the upper open end thereof and just below the cover, said pouring breast having a discharge opening to permit of the dispensing of the contents of the pail in a controlled and well defined stream over the rim of the open end of the pail, but being of such shape and size as to leave a large and unobstructed opening at the upper end of the pail whereby the contents of the pail may be easily and thoroughly stirred.

2. A container of the character described having an open upper end, a closure adapted to have a liquid-tight seal with said upper open end, and a pouring breast secured to the pail and located adjacent to the upper open end thereof just below the closure, said pouring breast being of segmental form and having its curved edge provided with a flange permanently secured to the pail in such manner as to permit of the application and removal of the cover without disturbing the mounting of the pouring breast.

3. A container for lacquer comprising a pail having an open upper end, a closure for the open end having liquid-tight securing and sealing means with said pail, and a flat, plate-like pouring breast of segmental form positioned within said pail just below the closure and permanently secured thereto, said pouring breast having a restricted discharge port adjacent the rim of the pail to provide for the discharge of a controlled and well defined stream over the rim of the pail.

4. A container for lacquer comprising a pail having an open upper end, a closure for the open end having liquid-tight securing and sealing means with said pail, and a pouring breast positioned within said pail just below the closure and permanently secured thereto, said pouring breast having a restricted discharge port adjacent the rim of the pail to provide for the discharge of a controlled and well defined stream over the rim of the pail.

5. A container of the character described having an open upper end, said container

being entirely closed and imperforate except for its open upper end, a closure adapted to have liquid tight seal with said upper open end, and a pouring breast secured to the container and located entirely within the container and disposed adjacent to the upper open end thereof just below the closure, said pouring breast being adapted to facilitate dispensing of the contents of the container in a controlled and well defined stream over the rim of the upper open end thereof when the closure is removed.

6. A container of the character described including an imperforate body portion and an imperforate bottom connected to the body portion, the upper end of said body portion having an opening, a closure adapted to have a liquid tight seal with said upper end around said opening, and a pouring breast secured to the body portion of the container and located entirely within and adjacent to said opening just below the closure, said pouring breast having means for facilitating and effecting the dispensing of the contents of the container in a controlled and well defined stream over the rim of the opening of the container when the closure is removed.

7. A container having an opening and an internal pouring breast located entirely within the container and below said opening, and having a port to facilitate the dispensing of the contents of the container in a controlled and well defined stream over the margin of the opening thereof.

8. A container having an opening, an internal pouring breast located entirely within the container below said opening and having a port whereby it is adapted to effect the dispensing of the contents of the container in a controlled and well defined stream over the margin of the opening, and a closure for the opening adapted to be applied and removed independently of the pouring breast, said closure when applied coacting with the container to provide a completely closed liquid tight container structure.

In witness whereof, I hereto affix my signature.

ALFRED J. CHAMBERLAIN.
